UNITED STATES PATENT OFFICE.

FRANK S. IRVINE, OF HUNTINGTON, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed June 27, 1921. Serial No. 480,552.

To all whom it may concern:

Be it known that I, FRANK S. IRVINE, a citizen of the United States, residing at Huntington, in the county of Suffolk, State 5 of New York, have invented certain new and useful Improvements in Telephone Systems, of which the following is a full, clear, concise, and exact description.

This invention relates to telephone 10 change systems and more especially to those systems in which machine switching apparatus is used in the establishment of talking connections.

In certain types of systems where selective 15 switching devices are employed, particularly those adapted for the extension of connections in a full-automatic manner, the subscribers' lines terminate at the central office in the multiple banks of line finder switches. 20 To secure the advantages incident thereto, the subscribers' lines may be divided into relatively large groups, the capacity of the finder switches being adapted to correspond with the size of the line group. The finder 25 switches may be provided each with a plurality of brush sets, each set serving a subdivision or brush group of a major group of subscribers' lines.

The number of equivalent finder switches 30 necessary to serve a major group of lines depends upon the nature of the traffic in such group. In any event, a plurality of finders are provided and each line appears in a set of multiple terminals in all finders. 35 Considering the subdivision, all lines in a particular brush group appear in terminals of all the finders which are accessible by the corresponding sets of brushes. The same is true of each of the remaining brush groups.

According to one well-known construction, 40 the brushes are normally in a non-contacting relation with the terminal bank and the brush sets of all finders which serve the same groups of lines are arranged to be rendered operative by a common device. In order to prevent more than one switch making connection with a given line, which might result if two switches were started at the same time, it is necessary to preclude the 45 possibility of a simultaneous movement among the finders in response to the presence of simultaneous calls on the subscribers' lines. This is attained by utilizing a starting circuit common to all brush groups of

lines for starting in motion a single idle 55 finder switch. The starting circuit contains a corresponding element for each group, such as a relay contact, and may be closed at any group in response to a call therein, to start an idle switch. Once the starting circuit is 60 closed at a given group it is rendered unavailable to all other groups.

Owing to the series nature of a starting circuit of this character the first brush group has a preference over all other groups, the 65 second brush group a preference over all succeeding groups, and so on, in appropriating the starting circuit for use at a time when two or more brush groups contain co-existing calls. This means that, as between 70 any two groups, one has an inherent advantage over the other.

The object of the present invention is to provide means, in a system of the character 75 above outlined, whereby any group of lines which has appropriated a switch for use in extending a call is prevented from starting another switch in response to a second call therein until all other groups having lines on which simultaneous calls exist have started 80 switches to extend each of such lines.

A feature of the invention relates to the provision of a device individual to each group, which is operated whenever a call is extended in such group, and which is held 85 operated to prevent that group from extending a further call until an unsatisfied simultaneous call in every other group has been served.

These and other features contemplated in 90 the present invention will become more clearly understood from the detailed description given hereinafter and from the appended claims.

Referring to the drawing Figs. 1 and 2, 95 taken in order, illustrate a portion of a mechanical exchange system embodying the subject-matter of this invention. Fig. 1 shows a portion of each of three successive brush groups of subscribers' lines entering 100 the central office together with certain control elements individual to the different lines, and other elements common to all the lines of a brush group, while still other devices are illustrated common to all brush groups. 105 Fig. 2 illustrates in diagrammatic manner a part of each of two groups of equivalent line finder switches, in the terminal banks of

which, the subscribers' lines appear. This figure further shows common controlling mechanism operating in conjunction with the controlling devices of the different brush groups to select and start in motion the finder switches in response to incoming calls.

The line finder switches, in Fig. 2, are of the panel power-driven type comprising a plurality of sets of brushes mounted on a vertically movable brush shaft, the brushes of the brush sets being designed to normally move over the terminals of the bank without engaging the same and arranged when taken for use to be tripped into contact relation with the terminals by a trip rod common to a number of different switches. The details of the construction and operation of a switch of this character are shown and described in the patent to J. L. McQuarrie No. 1,177,044, issued March 28, 1916.

The sequence switches such as the switch 218 shown in the drawing, one of which is provided for controlling the circuits of each line finder switch and its associated selector switch, are of the well-known type such, for example, as the one described in the patent to E. B. Craft and J. N. Reynolds No. 1,123,696, issued January 5, 1915.

In order that a better understanding may be had of the purpose of the invention, a general description will first be given of the grouping arrangement of the calling subscribers' lines before proceeding with the details of the operating circuits. It may be assumed, for illustration, that the calling subscribers' lines such as lines 100, 120, 130, 140, etc., are divided into major groups of 300 lines each. Accordingly, the finder switches, in the terminal banks of which the subscribers' lines appear, have a capacity for accommodating 300 lines. It may further be considered that the finder switches are provided with fifteen sets of brushes, each set of brushes consequently having access to twenty different subscribers' lines. In order to give adequate service to a group of 300 lines, a number of finder switches are provided to each such group. These finders are arranged in two groups, half of the finders appearing in the A group and the other half in the B group as indicated in Fig. 2. The twenty subscribers' lines of each brush group appear before the corresponding brushes of all finder switches in both the A and the B groups. Furthermore, the brush groups of subscribers' lines are subdivided into two smaller groups of ten lines each. The first ten lines, known as the A subgroup, appear in the lower half of the section served by the brushes of all finders in the A group of finders and appear in the upper half of the section served by the corresponding brushes of the finders of the B group. Similarly, the second ten

lines, known as the B subgroup of the brush group, appear in the upper half of the section served by the brushes of the finders of the A group and in the lower half of the section served by the corresponding brushes of the finders in the B group. In other words, all of the fifteen brush groups of lines are subdivided into two subgroups, the A subgroup and the B subgroup. The A subgroups of the brush groups appear as first choice lines in the lower half of the sections served by the corresponding sets of brushes in the A finders and as second choice lines served by the brushes of the B finders. The same is true of the B subgroups of all brush groups, they appearing as first choice lines in the lower half of the sections served by the corresponding brushes of the B finders and as second choice lines in the upper half of the sections served by the brushes of the A finders.

By such an arrangement the finder switches in the A group may normally serve calls appearing in the A subgroups of lines whereby these switches will only be required to traverse a maximum distance corresponding to ten sets of terminals. Likewise, the B finders normally serve the B subgroups of lines. Whenever, a call occurs in either an A or B subgroup, a finder normally serving such group will be taken for use provided an idle finder is available at the time. If, however, all finders of the A group are busy when a call occurs in an A subgroup, or if all finders of the B group are busy when a call occurs in a B subgroup, then a finder in the other group will be taken for use, in which case, the operating finder will be required to pass over the first ten sets of terminals in each brush group before it can make connection with the terminals of the calling line. For a more complete description of a line finder system wherein the brush groups of lines are subdivided into smaller groups and appear non-correspondingly in the terminals of two different groups of equivalent line finder switches, reference is made to the application of S. B. Williams, jr., Serial No. 348,510, filed December 31, 1919, Patent No. 1,380,857, issued June 7, 1921, and also to applicant's copending application, Serial No. 411,880, filed September 22, 1920, Patent No. 1,461,528, issued July 10, 1923.

In Fig. 1 of the drawing three of the fifteen brush groups of lines are illustrated. Only two lines, namely, lines 100 and 120 of the first brush group are shown. The line 100 is one of the ten lines of the A subgroup of the first brush group and its conductors 101 and 102 will be seen to appear in the terminals of the lower half of the section served by the brushes of the finders 200, 205 and 210 of the A group of finder switches. Only three finder switches of each of the A

and B groups have been shown, there being as many provided as the nature of the traffic warrants.

The first brush group of terminals of the 5 A finder switches are divided in accordance with the division of the brush group of lines into two sections, the lower section indicated at 232 and the upper section indicated at 233. In a like manner, the first brush 10 group of terminals of the finders 215, 220, 225, etc., of the B group is divided into two sections, the lower section 235 and the upper section 234.

Hence, the subscriber's line 100 which is 15 one of the ten lines of the A subgroup of the first brush group in addition to appearing in the lower or first choice section 232 of all finders of the A group also appears in the terminals of the upper section 234 of all 20 finders in the B group. The line 120, which is one of the lines in the B subgroup of the first brush group, appears as a first choice line in the lower section 235 of the B 25 finder switches and also as a second choice line in the upper section of terminals 233 of the A finder switches.

Lines 130 and 140 are respectively lines in the A and B subgroups of the second brush group of lines and appear in a similar fashion in the terminals of the A and B 30 groups of finder switches served by the second brush sets. At the lower part of Fig. 1 the elements belonging to the third brush group of subscribers' lines are shown. Although the lines for this brush group have 35 been omitted, it is understood that they, too, will appear before the third brush sets of the finders of both the A and B groups.

Inasmuch as all brush groups of a major 40 group of lines are served by a plurality of different line finder switches and since lines in the same or in different brush groups may initiate calls simultaneously, some systematic arrangement is required whereby 45 idle switches may be chosen and taken for use to find the calling lines without interference. To this end a common starting mechanism consisting of relays shown in Figs. 1 and 2 is provided for all brush 50 groups of lines and operates to start an idle line finder in either of the A or B groups dependent upon the location of the calling line. This starting mechanism is rendered effective by the completion of a starting circuit which extends in series to all of the several brush groups. Upon the initiation of 55 the call in any brush group, the starting circuit is modified at a point corresponding to that group and taken temporarily for the sole use thereof to the exclusion of all remaining groups. As soon as a finder is started the starting circuit is restored to its normal condition and becomes available for calls in the same or other groups. Due to 60 the series nature of this starting circuit the

first brush group in the series has an inherent advantage over all succeeding groups of lines in the matter of appropriating the starting circuit at a time when a call is initiated in such group simultaneously with the 70 initiation of a call in any of the remaining groups. The second brush group, which is subservient only to the first brush group, has an advantage over all remaining groups of simultaneous calls. Likewise, the third brush 75 group has a preference over all succeeding groups and so on to the last group in order, which has the least opportunity of all in appropriating the starting circuit. With such an arrangement, any group may successfully 80 start the line finder to serve its calling lines without delay provided no other group contains a co-existing call, but where two or more lines in different groups initiate calls simultaneously, some one group thereof will 85 always have the preference and the other will be required to wait. To overcome this objectionable feature inherent to the simple series starting circuit, a relay such as the relays 109, 137 and 143 is provided for each 90 brush group of lines together with a relay 145 common to all groups. Considering the first brush group, for example, the relay 109 is always operated during the process of starting a line finder switch to find a calling 95 line in this group. The relay 109, which controls the starting circuit, as will be seen hereinafter, deenergizes shortly, provided no other group contains a simultaneous call, and by deenergizing renders the first group 100 in condition to again initiate the movement of a finder switch to serve a subsequent calling line. However, if some other group contains a co-existing call, the relay 145 will be 105 energized and relay 109 upon operating in the first group will remain energized. Relay 109 thus remains locked to prevent any other line in the first group from initiating a subsequent call until a call originated 110 simultaneously in each of the remaining groups has been satisfied.

A detailed description of the operation will now be given. Assume at first that the subscriber of some one of the ten lines in the A subgroup of the first brush group, such as the subscriber of line 100, desires to obtain a telephone connection. Upon removing his receiver from the switchhook the subscriber completes a circuit from battery through the winding of the line relay 103, inner contact of cut-off relay 104, conductor 102, through the substation loop of line 100, conductor 101, outer contact of relay 104 to ground. The line relay 103 operates and closes a circuit from ground through its left contact, winding of group relay 105, normal contacts at the inner right armature of said relay, conductor 149, innermost contact of relay 146 to battery. Relay 105 120 which is common to all the line relays 103, 130

106, etc., of the A subgroup of the first brush group operates in the circuit traced and locks in a circuit from battery through its inner right armature and contact and 5 winding of relay 105 to ground at the left contact of relay 103. Immediately that relay 105 becomes energized a circuit is closed from ground through its left armature and contact, conductor 114, outer left contact of 10 relay 109, conductor 148, winding of relay 145 to battery. Relay 145 energizes in this circuit. Relay 105 also establishes a circuit from ground through its left contact, conductor 115, inner right contact of relay 108, 15 which relay is common to all lines in the brush group, inner back contact of relay 111, right contact of relay 109, left-hand winding of relay 110, conductor 116, next to the inner contact of relay 146 to battery. The 20 relays 111 and 110 above mentioned are also common to all twenty lines in the first brush group. Relay 110 becomes energized in the circuit traced and completes the starting circuit from ground through the outer contact 25 of relay 108, right-hand winding of relay 110, inner right front contact of relay 110, conductors 117 and 118, winding of starting relay 146 to battery. Relay 146 operates to open the original energizing circuit 30 through the left-hand winding of relay 110, but relay 110 remains operated in the circuit just traced through its right-hand holding winding and the winding of relay 146. A circuit is now established from ground 35 through the next to the outer contact of relay 146, conductor 119, outer left contact of relay 110, winding of relay 111 to battery. Relay 111 operates and locks in a circuit from battery through its winding and inner front contact and inner right contact 40 of relay 108, conductor 115, left contact of relay 105 to ground. Relay 111 closes a circuit from ground through its outer contact, right-hand winding of relay 109 to battery. 45 Relay 109 at its outer left contact opens the circuit traced for relay 145 and this latter relay becomes deenergized, since it is assumed that in the case under discussion no other group of lines is making a simultaneous call.

The starting relay 146 also prepares a circuit from ground through the next to the outer contact, conductor 119, inner left contact of relay 110, conductor 150, outer right contact of relay 105, conductor 151, conductor 152, back contact of relay 201, left contact of relay 202, outer back contact of relay 203, lower contact of spring 213 of sequence switch 218 closed in position 1, innermost left contact of relay 208, right-hand winding of relay 209 to battery. Since the first line finder switch 200 in the A group is assumed to be idle, sequence switch 218 individual to such line finder is in its normal position, position 1, and hence the lower

contact of spring 213 is closed and the relay 209 is deenergized. The relay 209 operates in the circuit traced and closes a holding circuit for itself from battery through its right-hand winding, inner left contact and left-hand winding of said relay to ground through the contact of relay 212. Relay 209 completes a circuit from ground through its outer left front contact, middle left contact of relay 208, normal contact at the right 75 armature of relay 202, winding of relay 202 to battery. Relay 202 becomes energized and locks in a circuit from battery through its winding and right front contact, conductor 243, outermost contact of relay 146 to 80 ground. Relay 202 at its left contact opens the circuit previously traced through the right-hand winding of relay 209, but relay 209 remains operated in the locking circuit as above explained. 85

Relay 209 also completes a circuit from ground through its right contact, winding of the updrive power magnet 236 to battery. The power magnet 236 of the chosen line 90 finder 200 is energized and acts in the well-known manner to cause the brush shaft 227 to move upwardly for the purpose of tripping the particular set of brushes which has access to that section of the terminal bank containing the terminals of the calling line. 95 It will be noted that the relay 110 at the time of operating also establishes a circuit from ground through its outer right contact, conductor 153, winding of trip magnet 237 to battery. Relay 110, being common 100 to all of the lines of the first brush group, always responds to the initiation of a call on any line in that group to complete the circuit traced over conductor 153 for the energization of the trip magnet 237 which 105 controls the tripping of the brushes at each of the line finders in both the A and the B groups having access to the first group of lines. Consequently, the magnet 237 when 110 energized moves the common trip rod 244 into a position such that, upon the upward movement of the brush shaft 227 of the selected switch, the brushes are tripped into operative relation with the terminals of the bank. 115

Shortly after the brush shaft 227 has commenced its upward movement and prior to the time the tripped set of brushes encounter the terminals of the first line, the brush 239 makes engagement temporarily with segment 240. A circuit is thereupon momentarily established from ground through brush 239, segment 240, conductor 117, conductor 118, winding of starting relay 146 to battery. It 120 will be noted that the circuit for the flow of current from battery through the winding of relay 146 to ground at the brush 239 is in shunt of the path previously traced through the right-hand holding winding of relay 110. Hence, relay 110 being shunted 125 130

releases its armatures and in so doing opens the circuit of trip magnet 237 allowing the trip rod 244 to be restored to normal so as not to cause the tripping of the corresponding sets of brushes on any other line finder switch, provided such a switch is moved. Relay 110 also opens the circuit traced for the energization of relay 209. Furthermore, relay 110 at its inner right contact connects the starting conductor 117 through to the corresponding contact of the relay 139 at the next brush group, whereby a call originating in any other brush group may cause the starting of another line finder switch. When the brush 239 moves off the segment 240, the circuit of relay 146 is opened and since relay 110 is now deenergized the original energizing circuit of relay 146 is also severed and this latter relay retracts its armatures.

As soon as the brushes 222, 223, 224 and 226 engage terminals 245, 246, 247 and 248 of the calling subscriber's line 100, a circuit is established from battery through the winding of relay 212, brush 226, terminal 248, conductor 113, right contact of line relay 103, left hand winding of relay 108 to battery. It will be noted that a circuit is closed through the right hand winding of relay 108 at the time relay 111 operates. The right-hand winding of relay 108, however, is so constructed that the flux created thereby is insufficient to operate the relay, but will maintain the armatures in their operated position once they have been attracted. Relay 108 now operates in the circuit traced through its left-hand winding and opens the locking circuit of relay 111. Relay 111, being slow to deenergize, requires an appreciable interval to retract its armatures.

Relay 212 opens the circuit of relay 209, but this relay remains energized an instant longer by means of a holding circuit from battery through its right-hand winding, inner left contact and left-hand winding of said relay, conductor 242, commutator 241, brush 239 to ground. When the brushes 222, 223, 224, and 226 are accurately centered on the terminals of the calling line, the brush 239 engages an insulating segment of commutator 241. The holding circuit of relay 209 is opened and this relay deenergizes. Relay 209 at its right contact opens the circuit of the updrive power magnet 236 causing the brush shaft 227 to cease its upward movement. At the time the brush shaft 227 moves away from its normal position the off-normal contact 217 is closed to complete an energizing circuit for relay 211. With relay 211 operated and relay 209 deenergized, a circuit is closed from battery through the winding of sequence switch magnet 218, contact of spring 219 (1), outer contact of relay 211, outer left back contact of relay 209 to ground. The sequence switch 218 advances

out of position 1 into its succeeding positions. Relay 211 also closes a circuit from battery through the winding of relay 208 to ground at the inner contact of relay 211. Relay 208 serves to indicate the busy condition of the line finder switch.

With the sequence switch 218 in one of its advanced positions, a circuit is closed from battery over conductor 249, brush 224, terminal 247, conductor 112, winding of cut-off relay 104 to ground. The manner in which this circuit is completed for the cutoff relay is shown in the above mentioned application, Serial No. 411,880, filed September 22, 1920. Relay 104 operates and opens the circuit of the line relay 103 causing this relay to become deenergized. Relay 103 opens the circuit of the group relay 105 which also releases its armatures provided no other line in the A subgroup is calling and has its line relay energized. As soon as the line relay 103 releases its armatures, it opens the operating circuit through the left-hand winding of relay 108. Relay 108, however, is held energized by means of a circuit through its right-hand winding to ground at the outer contact of the slow-to-release relay 111. As soon as the necessary interval has elapsed, the relay 111 retracts its armatures and opens the circuit of relay 108, whereby this relay also becomes deenergized. Relay 111 at its outer contact opens the circuit through the right-hand winding of relay 109 and relay 109 releases its armatures due to the fact that the common relay 145 has already become deenergized.

After conversation is completed and connection is no longer required, the brush shaft 227 of the operated finder switch is restored to its normal position in the well-known manner.

Should the first line finder switch 200 be busy when the subscriber's line 100 initiates the call in the A subgroup, then sequence switch 218 is standing in some position other than position 1 and the circuit previously traced for relay 209 by way of conductor 152, back contact of relay 201, left contact of relay 202 and the outer back contact of relay 203 now leads over the upper contact of spring 213 (2+18), lower contact of spring 214 (1) of the sequence switch individual to the next line finder 205, provided this switch is idle at the time, conductor 250, and thence through the right-hand winding of a relay corresponding to relay 209 to battery. In this manner the second line finder 205, which is the first idle switch available at the time, is started in operation to find the calling subscriber's line.

Consider next that the subscriber of line 120, which is one of the ten lines in the B subgroup of the first brush group, wishes to extend a telephone connection. Upon removing his receiver from the switchhook a cir-

cuit is established from battery through the winding of line relay 123, inner contact of cut-off relay 124, conductor 122, over the loop of the calling line, conductor 121, outer contact of relay 124 to ground. The line relay 123 operates and closes a circuit from ground through its left-hand contact, winding of relay 125, the normal contact at the inner right-hand armature of said relay, conductor 149, innermost contact of relay 146 to battery. Relay 125 which, like relay 105 is common to all of the ten lines of the B subgroup, is operated in response to the energization of any of the line relays such as relays 123, 126, etc. Relay 125, upon operating, locks in a circuit from battery through its inner right contact, winding of said relay to ground at the left contact of relay 123. Relay 125 establishes a circuit from ground through its left contact, conductor 114, outer left contact of relay 109, conductor 148, through the winding of relay 145 to battery, causing the energization of relay 145. Relay 125 also completes a circuit from ground through its left contact, conductor 115, inner contact of relay 108, inner back contact of relay 111, right contact of relay 109, left-hand winding of relay 110 and thence over conductor 116 as formerly traced to battery. Relay 110 becomes energized in this circuit and closes the above traced locking circuit for itself through its right-hand winding and the winding of the starting relay 146. Relay 146 operates and opens the circuit through the left-hand winding of relay 110. Relay 110 closes a circuit for relay 111, causes the energization of the trip magnet 237 and also completes a circuit from ground through the next to the outer contact of relay 146, conductor 119, inner left contact of relay 110, conductor 154, outer right contact of relay 125, conductor 155, back contact of relay 204, left contact of relay 207, outer back contact of relay 206, conductor 251, lower contact of spring 221 of the sequence switch individual to the finder 215 of the B group, closed in position 1, provided this finder is idle, conductor 252, and thence through the winding of a relay corresponding to relay 209. The finder switch 215 is thus started in operation to hunt for and find terminals of the calling line 120 in the B subgroup, which line appears as a first choice line in the B finder switches.

When the finder switch 215 moves away from normal position, the brushes 253, 254, 255 and 256 are tripped due to the displaced condition of the common trip rod 244 and make engagement with their cooperating terminals. Also, upon the initial movement of the brush shaft, a brush similar to brush 239 encounters a segment similar to segment 240 placing a ground upon the common conductor 117 which shunts the relay 110. Re-

lay 110 deenergizes and an instant later the starting relay 146 retracts its armatures as previously explained. From this point on the operation of the finder switch to find and seize the terminals of the calling line 120 proceeds in the same manner as already explained in connection with the finder switch 200. When the line is found and the cut-off relay 124 has been operated for a sufficient interval, relay 111 becomes de-energized, permitting the release of relays 108 and 109.

It may occur at certain times that all of the finders in either the A or B groups are simultaneously busy when a call is initiated in one of the subgroups of any brush group served as first choice by these finders. In such a case, one of the finders of the group serving the calling line as a second choice will be taken for use provided such groups contain an idle switch. For example, if the subscriber of line 100 initiates a call when all of the finders of the A group which normally serve this line are busy, then one of the finders in the B group is appropriated for extending the line. Referring to Fig. 2 it will be observed that the circuit through the outer left contact of relay 208 extends thereafter through contacts of similar relays for other finders, and thence to ground. This particular convention means that the circuit includes the outermost left contact of a relay corresponding to relay 208 of each of the remaining finders 205, 210, etc., of the A group of switches. Hence when all of the finders are busy and all of the relays similar to relay 208 are operated, this series circuit is closed through the left-hand winding of relay 203 to battery. Relay 203 operates. When under these conditions the subscriber of line 100 initiates the call and relays 110 and 146 are energized a circuit is established from ground through the next to the outermost contact of relay 146, conductor 119, inner left contact of relay 110, conductor 150, outer right contact of relay 105, conductor 151, conductor 152, back contact of relay 201, left contact of relay 202, outer front contact of relay 203, winding of relay 204 to battery. Relay 204 operates and establishes a circuit from ground through its front contact, left contact of relay 207, outer back contact of relay 206, conductor 251, and thence to the relay corresponding to relay 209 at the first idle finder switch in the B group of switches. This switch is, therefore, started in operation, moves over the first group of ten terminals which it normally serves and into the second group of ten terminals to find and seize the calling subscriber's line 100. A similar series of operations occur whenever a line in the B subgroup calls at the time when all finders of the B group of finders are simultaneous-

ly engaged and one of the A finder switches is taken for use.

To illustrate the purpose of the series starting circuit, the next case to be considered is the one wherein the subscriber of the line in the second brush group extends a call at a time when no waiting calls exists in the first brush group. Assume that the subscriber of line 130 wishes to obtain a telephone connection. On removing his receiver from the switchhook, a circuit similar to the one already traced is established for the line relay 133, which in turn, causes the energization of the group relay 135. The group relay locks in an obvious circuit and establishes a circuit from ground through the left contact of relay 135, conductor 156, outer left contact of relay 137, which like relay 109 is common to the second brush group, conductor 148, winding of relay 145 to battery. Relay 135 also closes a circuit from ground through its left contact, conductor 157, inner contact of relay 136, inner back contact of relay 138, right contact of relay 137, left hand winding of relay 139, thence over conductor 116 to battery. Relay 139 operates and closes a circuit from ground through the outer contact of relay 136, right hand winding and inner right front contact of relay 139, conductor 158, inner right back contact of relay 110, which relay is deenergized at this time, starting conductor 117, conductor 118, winding of starting relay 146 to battery. Relay 146 operates and relay 139 remains locked in this circuit. Relay 146 also completes a circuit from ground through the next to the outer contact of said relay, conductor 119, outer left contact of relay 139, winding of relay 138 to battery. Relay 138 operates and locks in a manner similar to that explained in connection with relay 111 and also closes a circuit for the energization of relay 137. Furthermore, relay 146 closes a circuit from ground through the next to its outermost contact, conductor 119, inner left contact of relay 139, conductor 159, outer right contact of relay 135, conductor 160, conductors 151 and 152, and thence as previously traced through the winding of relay 209 of the finder switch 200. Relay 139 in addition closes a circuit from ground through its outer right contact, conductor 161, winding of trip magnet 238 to battery. The trip magnet 238 positions the common trip rod 257 preparatory to tripping the set of brushes having access to the second brush group of lines at any finder switch which is moved upwardly. The operation of the finder switch 200 to seize the terminals of the calling line 130 proceeds in the manner now well understood.

It will be observed that when the relay 110 of the first brush group is operated during the interval that the finder switch is be-

ing started to seize a calling line in that group, the conductor 117 is disconnected from conductor 158 and thereby from all succeeding brush groups at the inner right back contact of said relay. This means that until a finder switch has been started to serve a call in the first group and relay 110 again becomes deenergized, no call in any succeeding group which has been made simultaneously or shortly subsequent to the call in the first group can receive attention. The same is true of the group relay 139 which is operated during the interval a finder switch is being started to seize a calling line in the second brush group. That is to say, with relay 139 energized, the starting circuit extending over conductors 117 and 158 is disconnected from the conductor 162 and hence from all succeeding brush groups, whereby calls in these groups cannot be served until both relays 110 and 139 are deenergized. The same relation exists throughout all succeeding brush groups of lines.

Assume next that two calls are made simultaneously, one of which occurs on any line in the first brush group such as either line 100 or line 120 and the other call on any line in the second brush group such as line 130 or line 140. In response to these calls both relays 110 and 139 are energized over the circuit previously traced through their left-hand windings. Relay 110, locks in the circuit traced through its right-hand winding and inner right front contact, conductor 117, and thence through the winding of relay 146 to battery. When relay 146 energizes in this circuit it opens the operating circuit for the left-hand winding of relay 139 and relay 139 deenergizes, since it cannot lock through its right-hand winding due to the fact that conductor 158 is disconnected from conductor 117 at the inner right back contact of relay 110. Hence, the calling line in the first brush group will receive immediate attention, while the calling line in the second group must wait until a finder has been started and relays 110 and 146 have deenergized to complete the starting circuit. Immediately when these relays become deenergized, relay 139 is again operated in a circuit over its left-hand winding and this time succeeds in locking through its right-hand winding and the winding of relay 146, whereby another finder switch is started to seize the calling line in the second brush group.

Should a call have existed simultaneously in the third brush group, it would be required to wait until both of the calls in the first and second groups have been taken care of before relay 144 could succeed in closing a locking circuit for itself in series with the starting relay 146.

Were some provision not made, several

simultaneous calls in the first brush group would receive attention in preference to any call in a succeeding group which may have been initiated at the same time. For as soon as relay 110 had deenergized after starting a finder to find one of the calling lines in the first brush group, it would immediately re-energize due to the existence of another call in such brush group thereby preventing the corresponding relay of any succeeding group from closing a locking circuit for itself. The provision for avoiding this undesirable feature will now be explained. At the time relay 111 operates following the energization of relay 110 which serves to start a finder to find the calling line, the relay 109 is also energized. Relay 109 at its outer left contact opens the energizing circuit of relay 145. If, at this instant, a line in some other brush group, such as the line 130 in the second brush group, is calling, the group relay 135 is operated and a circuit is closed from battery through the winding of relay 145, conductor 148, outer left contact of relay 137, conductor 156 to ground at the left contact of relay 135. Consequently, the energization of relay 109, while it opens one of the branches of the circuit for operating the relay 145, is without effect upon this relay, since another of the branches of the operating circuit of said relay is closed at the left contact of relay 135 due to the fact that a line in the second brush group is calling. When, after the calling line in the first brush group has been found, relay 111 deenergizes, it opens the operating circuit through the right-hand winding of relay 109. Relay 109, however, cannot release its armatures due to the circuit closed from battery through the left-hand winding and inner left contact of said relay, conductor 147, contact of relay 145 to ground. Relay 109, therefore, remains operated due to the fact that relay 145 is still energized which indicates that a call in some other brush group is awaiting attention.

Should there be one or more other calling lines in the first brush group, relay 105 or relay 125 is operated as the case may be, but the relay 110 cannot again be energized since the operating circuit through its left-hand winding is held open at the right contact of relay 109. With the relay 110 deenergized the starting circuit is extended through to the second brush group and relay 139 is now operated and locks through its right-hand winding over conductor 158 and conductor 117, and thence through the winding of the starting relay 146. A finder is thereupon started to extend the calling line 130 in the second brush group.

As soon as relay 139 locks in series with relay 146, relay 138 is operated and causes the energization of relay 137. Relay 137 opens the branch of the circuit which held

the common relay 145 energized and relay 145 becomes deenergized provided that no line in any other succeeding group is calling at this time. Immediately that relay 145 retracts its armature it opens the holding circuit of relay 139 and this relay becomes deenergized to permit other calls which may be existing in the first brush group to cause the energization of relay 110 to start line finders. If, however, a call is simultaneously existing in some other brush group at the time relay 137 becomes operated, relay 145 is still held energized over a branch of its operating circuit closed at such other group.

By means of this arrangement no brush group of lines, regardless of the inherent advantage it may have over other brush groups, can succeed in establishing more than one connection until a call is satisfied in every other group having simultaneous calls therein.

In case one or more lines in every brush group is making a simultaneous call, the relay 145 operates over parallel branches closed at the group relays 105, 135, etc., and as the relays 109, 137, 143, etc., operate, they lock to the contact of relay 145. The relay 145 remains energized to prevent the de-energization of relays 109, 137, 143, etc., after they have once operated, to prevent another call from being extended in their respective groups until a call has been served in each and every other group having a calling line therein. At this time the last parallel branch for holding the relay 145 is opened and this latter relay releases to, in turn, open the holding circuits of all relays 109, 137, 143. With these relays all released, a call in the first group, provided there exists one, may be made and so on in the same manner as before.

What is claimed is:

1. In a telephone system, a number of groups of lines, one of said groups including a first line and a second line and another of said groups including a third line, a plurality of automatic switches serving said lines, means responsive to the initiation of a call on any of said lines for operating one of said switches to extend such line, means operative when a switch is being taken for use to extend said first line for rendering said second line ineffective to operate a switch provided a call exists on said third line, and means for rendering said second line effective to cause the operation of a switch as soon as the switch taken for use by said third line commences to operate.

2. In a telephone system, a number of groups of lines, one of said groups including a first line and a second line, another of said groups including a third line, a plurality of finder switches serving said lines, means responsive to the initiation of a call on any of said lines for

- moving one of said switches to extend such line, means operative when a switch is being taken for use to extend said first line for rendering said second line ineffective to 5 operate a switch provided a call exists on said third line, means effective as soon as the switch taken for use by said first line has commenced to operate for rendering said third line effective to operate one of said switches, 10 and means for rendering said second line effective to cause the operation of a switch as soon as the switch taken for use by said third line commences to operate.
3. In a telephone system, a plurality of 15 groups of lines, a plurality of automatic switch serving said lines, means responsive to the initiation of a call on any of said lines for moving one of said switches to extend such line, means operative when a switch 20 is being taken for use to extend a line in any particular group for rendering the remaining lines in such group ineffective to move one of said switches provided a call exists on a line in any other group, and 25 means for rendering a second line in said particular group effective to cause the operation of a switch as soon as the switch taken for use by the calling line in said other group commences to operate.
- 30 4. In a telephone system, a plurality of groups of lines, a plurality of automatic switches serving said lines, means responsive to the initiation of a call on any of said lines for moving one of said switches to 35 extend such line, and means operated when a switch is being moved to extend a line in any particular group, if some other group contains a simultaneously calling line, for rendering the remaining lines in said par- 40 ticular group ineffective to move one of said switches until said simultaneously calling line has been extended.
5. In a telephone system, a plurality of 45 groups of lines, a plurality of automatic switches serving said lines, means responsive to the initiation of a call on any of said lines for moving one of said switches to extend such line, and means operated when a switch is being moved to extend a line in 50 any particular group, if other groups contain simultaneously calling lines, for rendering the remaining lines in said particular group ineffective to move one of said switches until all the simultaneously calling lines in said other groups have been ex- 55 tended.
6. In a telephone system, a plurality of groups of lines, a plurality of automatic switches for extending said lines, means re- 60 sponsive to the initiation of a call on a line in any particular group for moving one of said switches to extend such line, means for rendering a second simultaneously calling line in said particular group ineffective to move one of said switches until the switch 65
- responding to said first line has started in motion, and means operated when a switch is being moved to extend a line in said particular group for rendering the remaining lines in such group ineffective until any line 70 in any other group which may be calling simultaneously has caused the movement of a switch for extending the same.
7. In a telephone system, a plurality of 75 groups of lines, a plurality of automatic switches for serving said lines, means for initiating a number of calls in each of said groups simultaneously, means for operating said switches to extend a calling line in each of said groups successively, means when a calling line in the last group has been ex- 80 tended for operating switches to extend a remaining calling line in each of said groups successively in the same order, and means for rendering a second calling line in any 85 group ineffective to operate a switch until a simultaneously calling line in each of all other groups has been extended.
8. In a telephone system, a plurality of 90 groups of lines, a plurality of automatic switches for extending said lines, means re- 95 sponsive to the initiation of a call on any one of said lines for moving one of said switches to extend such line, a plurality of relays individual respectively to said groups, means when a line in any particular group initiates a call to move one of said switches for operating the relay individual to such particular group, and means re- 100 sponsive to calling lines in other groups for maintaining said relay operated to render all remaining lines in said particular group ineffective to move one of said switches until said calling lines in other groups have been extended. 105
9. In a telephone system, a plurality of 110 groups of lines, a plurality of automatic switches for extending said lines, means re- 115 sponsive to the initiation of a call on any one of said lines for moving one of said switches to extend such line, a plurality of relays individual respectively to said groups, a common relay for all groups, means when a line in any particular group initiates a call to move one of said switches for operating the relay individual to such particular group, means responsive to calling lines in other groups for operating said common relay, and means controlled by the common relay for maintaining operated the 120 relay individual to said particular group to render the remaining lines in such particu- 125 lar group ineffective to move one of said switches until said calling lines in other groups have been extended.
10. In a telephone system, a plurality of 130 groups of lines, a plurality of finder switches serving said lines, means re- 135 sponsive to the initiation of a call on any one of said lines for starting one of said switches

in motion to find and extend such line, and means operated when a finder switch is being taken for use to extend a line in any particular group for rendering the remaining lines in such group temporarily ineffective to start another of said switches provided a call exists on a line in some other group.

11. In a telephone system, a plurality of groups of lines, a group of finder switches each having a plurality of brush sets, each brush set serving a group of said lines, means responsive to the initiation of a call on any line in any group for selecting the proper brush set of an idle finder switch and for starting such switch in motion to find the calling line, and means operated at the time a switch is taken for use to extend a line in any particular group for rendering the remaining lines in said group tem-

porarily ineffective to start another idle switch provided a call exists on a line in some other group.

12. In a telephone system, a plurality of groups of lines, a plurality of automatic switches for serving said lines, means for initiating a plurality of simultaneous calls, one on a line in each group, means for operating said switches to extend the calling lines successively in a certain order, and means when any group contains a second simultaneously calling line for rendering such second line ineffective to operate a switch for extending the same until a simultaneously calling line in each of all other groups has been extended.

In witness whereof, I hereunto subscribe my name.

FRANK S. IRVINE.
